UNITED STATES PATENT OFFICE.

WILLIAM DIETZEL, OF MERRICK, NEW YORK.

CLOTHESLINE HANGER.

Application filed April 19, 1922. Serial No. 555,547.

To all whom it may concern:

Be it known that I, WILLIAM DIETZEL, a citizen of the United States, and a resident of Merrick, in the county of Nassau 5 and State of New York, have invented a new and Improved Clothesline Hanger, of which the following is a full, clear, and exact description.

This invention relates to clothesline 10 hangers and particularly to an improved construction which may be secured to a window frame, the construction being such that when secured in place part of the hanger may be swung through the window 15 when hanging clothes thereon and swung out of the window at another time.

The object in view is to provide a simple, 20 strong and inexpensive structure which will properly support the clothes and which may be easily operated.

Another object of the invention is to provide a hanger wherein means are provided which may be easily operated by an inexperienced person to cause the hanger to assume either of two positions according to 25 the desire of the operator.

A still further object of the invention is to provide a construction which may be readily fitted to windows of different sizes 30 and when in place operate in an efficient manner.

In the accompanying drawings—

Figure 1 is a longitudinal vertical section through part of a window frame and 35 associated parts together with a side view of a hanger disclosing one embodiment of the invention, said hanger being shown as extending through the window frame into the room.

Figure 2 is a view similar to Figure 1 but showing the hanger swung to an outer position.

Figure 3 is a sectional view through Figure 5 approximately on line 3—3.

Figure 4 is a sectional view through Figure 1 on line 4—4, the same being on an enlarged scale.

Figure 5 is an elevation of the construction shown in Figure 1.

Figure 6 is a top plan view of the construction shown in Figure 1, the same being on an enlarged scale.

Figure 7 is an enlarged fragmentary sectional view through Figure 5 on line 7—7.

Figure 8 is an enlarged fragmentary sectional view through Figure 5 on line 8—8.

Figure 9 is an enlarged fragmentary sectional view through Figure 5 on line 9—9.

Referring to the accompanying drawings by numeral, 1 indicates a window frame of 60 any kind which is provided with the usual upper and lower sashes 2 and 3. Connected with the two vertical sections of the frame 1 are clamping members 4 and 5 as shown in Figure 5, each clamping member being preferably constructed as shown in Figure 7 with a base section 6 bent at 7 for forming the top section 8, said top section overlapping the entire base section 6. The top section 8 is also provided with pressed out 65 beads 9 and 10 which beads form with the base 6 an opening through which the square bars 11 and 12 extend. These bars are each provided with a number of depressions 13 70 into which the respective depressions 14 and 15 75 formed in the beads 9 and 10 fit when the parts are properly positioned.

In case the window should be of less width than that shown in Figure 5, the nuts 16 and 17 may be loosened sufficiently to 80 allow the section 8 to spring outwardly away from the section 6 and thereby allow the respective clamping members 4 and 5 to slide longitudinally of the bars 11 and 12. When the clamping members have been 85 properly positioned for engaging the vertical walls of the frame 1, the depressions 14 and 15 will consequently be in one of the depressions 13 near the center of the respective bars 11 and 12. After this adjustment has been made the nuts 16 and 17 are tightened and the screws 18 placed in 90 position for holding the clamping members 4 and 5 properly to the frame 1. This construction permits a ready, easy and efficient 95 adjustment whereby the device may be used in connection with windows of different widths. It will be understood that the members 4 and 5 are identical so that the description of one will apply to both. 100

In the drawing, two bars 11 and 12 have been shown as this double bar arrangement makes a stiffer construction and less liable to spring out of line or strain the fastening members 4 and 5. Arranged centrally of the bars 11 and 12 or at some convenient point between ends, is a fixture 19 which fixture preferably consists of an inner plate 20 having any desired number of stiffening beads 21 formed thereon, a central plate or 105 section 22 bent at 23 for forming a spring hinged to an outer section 24 provided with 110

beads 25 and 26 through which the bars 11 and 12 extend. These bars are provided with depressions 13 near their centers for accommodating the depressed sections 27 5 and 28 of the beads 25 and 26. The various plates or sections 20, 22 and 24 may be held together by any suitable means, as for instance, by being spot-welded. These plates are provided with registering openings 29 10 through which one end of the auxiliary arm 30 extends. The auxiliary arm 30 is provided with a sharp bend 31 whereby the same acts as a hook for holding the arm in an extended position as shown in Figure 1 15 when clothes are being placed on the outgoing line 32. From the bend 31 a section 33 projects in a curve so that it may be readily engaged by the hand in order to lift the section 31 into registry with the openings 29 20 whereby it may pass therethrough and permit the parts to be moved to the position shown in Figure 2. The auxiliary arm 30 is made from a strong, stiff piece of metal and on the end opposite the hook 31 is welded or 25 otherwise rigidly secured to a pulley hood 34. This hood is provided with a pair of depending sections 35, each section having a pressed up bead 36 through which one of the rods or arms 37 or 38 extends, said arms 30 being welded or otherwise rigidly secured to these beads while their opposite ends are formed into eyes 39 and 40 rotatably mounted on the bar 12. The pulley wheel 41 is carried by the hood 34 and the clothesline 35 is designed to pass thereover, the arrangement being such that the incoming line 42 will pass over the top of the pulley when the parts are in the position shown in Figure 1 and the outgoing line will pass from 40 the lower part thereof.

When in use, the clothes are secured to the line 32 by clothespins or other suitable means and this line is gradually moved outwardly as the clothes are applied. When the desired supply of clothes has been placed on the line, the operator lifts the hook 31 until the same is in registry with the opening 29 whereupon the pulley wheel 41 and associated parts may be swung downwardly to 50 the position shown in Figure 2. Before the hook 31 is released in this manner, both the incoming and outgoing sections of the clotheslines 42 and 32 are placed on the hook 43 so that the line will have a substantially 55 right-angular turn as indicated in Figure 2 and the weight of the clothes will produce a substantially vertical pull against the pulley wheel 41 and rods 37 and 38. Ordinarily, this pull by the clothes is not sufficient to 60 swing the pulley wheel 41 but in case it should the hood 34 will merely strike against the sash 3 without doing any damage. The hook 43 is provided with a securing hook end 44 extending through a suitable aperture 65 in the fixture 19, said hook end being

preferably loosely positioned so that the hook 43 may readily adjust itself to any strain brought thereon.

After the parts have been moved to the position shown in Figure 2, the window sash 3 is lowered so that the window is completely closed. When it is desired to remove some of the clothes, the sash 3 is raised as shown in Figure 1 and the pulley 41 or arm 30 is grasped and the parts raised to the position shown in Figure 1. It will be noted that the end of the extension 33 projects through the opening 29 so that when the parts are raised in this manner the hook 31 will automatically snap into the position shown in Figure 3.

What I claim is:—

1. In a clothesline hanger of the character described, a supporting structure adapted to be connected to a window frame exteriorly thereof, a pulley, a pair of supporting rods connected to the pulley and pivotally mounted on said supporting structure, and an arm connected to said rods near said pulley said arm being formed with a catch adapted to interlock with said supporting structure.

2. In a clothesline hanger of the character described, a supporting structure adapted to be secured to the exterior of a window frame, a pulley supporting arm pivotally mounted on said supporting structure and positioned to swing through the window frame into the room and swing out to a position substantially exteriorly of the window frame, an auxiliary arm secured at one end to the pulley supporting arm formed with a catch adapted to engage said supporting structure when the pulley supporting arm is extending through the window frame for bracing said pulley supporting arm, a pulley carried by said pulley supporting arm, and a clothesline receiving hook carried by said supporting structure and adapted to have the clothesline looped thereover when said pulley supporting arm is swung to a position substantially exteriorly of said frame.

3. In a clothesline hanger of the character described, a supporting structure, comprising a bar square in cross section, a clamp for each end of said bar having a square passage-way therethrough, means for securing said clamp to the exterior part of a window frame, a fixture rigidly secured to said bar intermediate its ends, a pulley wheel, an arm for supporting said pulley wheel, and bracing means carried by said arm, said bracing means having one end connected to the outer end of said arm and the other end formed with a catch, said catch being adapted to interlock with said fixture when the arm is in an operative position.

4. The combination with a clothesline hanger formed with a support including a

pair of square bars, of a pair of clamps, each of said bars having depressions near each end, each of said clamps having pressed out sections fitting over said bars, each section having a depressed portion fitting into one of said depressions, and clamping bolts for clamping the parts of said clamps together.

5. In a clothesline hanger of the character

- 10 described, a supporting member provided with a pair of bars, square in cross section, a fixture carried by said bars provided with square passage-ways therethrough for accommodating said bars, said bars being each
- 15 provided with a depression while said fixture is provided with pressed sections fitting into said depressions whereby the fixture cannot move longitudinally of the bars, a pulley, a pair of rods for pivotally connecting the pulley with said fixture so that the rods may swing from a horizontal to a vertical position and a retaining arm for locking said rods against accidental movement when in a horizontal position.
- 20 6. In a clothesline hanger of the character described, a supporting structure including a pair of bars, a fixture secured to said bars intermediate their ends, a pair of rods hav-
- ing eyes at one end surrounding one of said bars, a pulley hood secured to the opposite ends of said rods, a pulley pivotally mounted in said hood, and an arm having one end secured to said hood and the opposite end formed with a hook adapted to snap over said fixture at a point spaced from said last mentioned bar when the pulley is in an elevated position.
7. In a clothesline hanger of the character described, a swinging arm, a pulley carried by said arm for supporting a clothesline, and a support for said swinging arm, said support including a pair of square bars and a pair of clamps, each of said bars having a plurality of depressions near each end and each of said clamps having pressed out sections fitting over said bars, each section having a depressed portion fitting into one of said depressions, said clamps being shiftable longitudinally of the bars so that the depressed portions thereof may fit into any of the depressions in said bars to accommodate different widths of windows, and clamping bolts for clamping the parts of said clamps together and against said bars.

WILLIAM DIETZEL.
